CAN OPENER

George Henning Gustafson, Los Angeles, Calif.

Application August 8, 1938, Serial No. 223,671

6 Claims. (Cl. 30—21)

This invention relates to can openers. One object is to provide a can opener that can be used with safety and efficiency on either cans or jars of various sizes having round tops. A further object is to provide a can opener that cannot be jammed by engagement with the rim of the can or with a seam in the can top. A further object is to provide a can opener that will not permit a totally severed can top to drop into the can.

A still further object is to provide a can opener which, in one form, is provided with a readily removable handle to permit removal and replacement of a blade that may be broken or dulled; and one provided with an automatically adjustable or semi-floating blade adapted to follow the edge or rim of the can during the cutting operation without the necessity of effort or attention or the requirement of skill on the part of the operator.

A still further object is to provide a can opener that may be used with safety and efficiency in opening cans that have been heated, this sometimes being desirable in the preparation of foods of certain kinds. With the foregoing and other objects in view the invention consists in the combination and arrangement of parts to be hereinafter fully described, pointed out in the claims and illustrated in the accompanying drawings, in which—

Fig. 1 is a top plan view of the can opener illustrating its application.

Fig. 2 is a view of Fig. 1 in side elevation.

Fig. 3 is a view similar to Fig. 2 but with the opener shown in an altered position.

Fig. 4 is an inverted fragmentary plan view of the opener.

Fig. 5 is an inverted plan view of a slightly modified form of guard from that shown in Fig. 4.

Fig. 6 is a top plan view of Fig. 5.

Fig. 7 is a vertical cross sectional view on the line 7—7 of Fig. 2.

Fig. 8 is a view in perspective of the sectional knife employed.

Fig. 9 is an enlarged detail vertical sectional view through Fig. 2 illustrating the knife assembly.

Fig. 10 is a detail plan view of a slightly modified form of opener showing a guard that may be employed.

Fig. 11 is a view of Fig. 10 in elevation showing its application to a can.

Fig. 12 is a view similar to Fig. 9 but showing a slightly modified knife assembly.

Fig. 13 is a vertical cross sectional view through Fig. 2 on the line 13—13.

Fig. 14 is a detail view, partly in section and partly in elevation, of a further slightly modified knife assembly.

Fig. 15 is a vertical cross sectional view through Fig. 14 on the line 15—15.

Fig. 16 is a view partly in section and partly in elevation of a further modified form of knife assembly.

Fig. 17 is an inverted plan view of Fig. 16.

Like reference characters denote corresponding parts throughout the several views.

The present can and jar opener comprises a shank having a removable handle at one end, a spur at the opposite end, the spur removably or permanently carrying a guard, and a knife adjustably arranged upon the shank. Guards of different types and knives and knife mountings of different types are provided. The reference numeral 1 denotes the shank of the opener, elongated, oblong in cross section, presenting opposed flat faces and provided at one end with the angular spur 2 and at the opposite end with the removable handle formed with a socket to receive the end of the shank. The body portion of the spur 2 is round in cross section and extends through and beyond the shank 1 and is fast thereto and provided upon one side of said shank with a round flat head 4 spaced above the shank, except in the form shown in Figs. 10 and 11 wherein the head of the spur is contiguous to one flat face of the guard, the spur upon the opposite face of the shank being bent forwardly beyond the adjacent end of the shank 35 almost parallel with the shank and having its termination pointed.

A guard of resilient material is carried by the spur upon the same side of the shank as the spur head. This guard may be made of rubber, rubber composition, or rubber upon one side and fabric upon the other.

As shown in Figs. 10 and 11 the guard 5 may be in the shape of a flat cam-shaped rubber disc, one or both flat faces being smooth, or one face may be formed with concentric circular ribs 6, this disc being permanently secured to the shank 1 by the spur 2 so that these members actually contact each other. This guard is of a thickness greater than the average can top, perhaps one-sixteenth of an inch, and of a spread or maximum diameter greater than that of a No. 2 can, the point of engagement of the guard by the spur being such that a straight line from the spur toward the handle parallel

to the shank and in the vertical plane thereof and terminating at the guard edge will be shorter than a continuation of this line from the spur to the opposite disc or guard edge; and a straight line at right angles to the shank and passing through the spur head to the guard periphery will be of substantially the same length upon each side of the spur.

In Figs. 1 to 7 inclusive slightly different and preferred types of guards are shown. They are made of substantially the same material but are intended for detachable engagement with the shanks and spurs. Each of these guards 11 and 12 is round, or of regular shape, instead of being cam-shaped and is formed upon one flat face, which will be termed its bottom face, with alternating rows of protuberances 7 and ribs 8 as in Figs. 1, 2, 3, 4 and 7; or with protuberances 9 arranged in concentric circles as shown in Fig. 5. While these guards are actually round they are provided with a pair of bracket or attaching straps of metal that cause them to assume the shape most clearly shown in Fig. 2 thus forming an upstanding lip portion 10 when the guard is seen in elevation.

A pair of bracket straps is secured to each guard 11 or 12 to give it shape, one strap 13 being flat and oblong and formed with a pair of depending prongs 14, the strap being disposed upon the top side of the guard and the prongs extending therethrough and through slots 15 in the cooperating strap 16 or 16a disposed upon the opposite or bottom side of the guard, said prongs being then bent flat against the strap 16 or 16a to provide the assembly. The strap 16 is of greater length than the strap 13 and is formed with an upwardly bent portion 17 that engages the guard and forces a portion of it against one end of the strap 13 thus forming the upstanding lip portion 10.

The strap 16 is provided with an elongated slot 18 that continues into the upturned strap end 17 and terminates in an enlarged portion 19, while the strap 16a is formed with a slot 18a that does not extend into its upturned end and that is formed with an enlarged end 19a. The slots 18, 19 and 18a, 19a permit the removable attachment of the guards 11 or 12 to the shank of the opener, the round head 4 of the spur being received through the enlarged slot and the spur then moved into the narrow slot. Friction between the spur head and the strap and guard will yieldingly retain the strap and guard in any adjusted position relative to the spur and shank but will permit manual oscillation or rotation of the guard about the spur as a pivot, one position of the guard being shown in Fig. 2, and a second position in Fig. 3, it being noted that in Fig. 2 the lip 10 is disposed toward the handle 3 while in Fig. 3 the lip is disposed away from the handle. With the lip 10 in the position shown in Fig. 3 the spur 2 may be forced through the top of the can 20 and the shank 1 then brought down into the cutting position shown in Fig. 2 and the guard moved back to operative position, there shown.

Slidably arranged upon the shank 1 is the knife carriage 21 of substantially inverted U-shape formation, one of the sides being slightly longer than the other and bent inwardly close to the base, both sides being perforated or slotted to receive the shank. Operatively supported between the sides of the carriage is the housing 22 that contains either the expansion coil spring 23 as shown in Figs. 7, 9, 12 and 13; or the rubber block 24 as shown in Fig. 15. The carriage shown

in Figs. 2 and 9 is provided with a two-piece knife, a detail of which is shown in Fig. 8. This knife has an elongated flat frame 25 with bent ends, one end having integral therewith the pointed tooth-shaped blade 26 extending downwardly outside the carriage, parallel and in spaced relation to a side thereof. The frame of the knife extends along the under side of the shank and passes through the slots in the sides of the carriage, the end remote from the blade 10 being notched to form the downturned prongs 27. The downturned blade end of the knife frame is formed with square corners that may ride against the rim of the can to guide the blade 26 clear of the rim.

The slot in the longer side of the carriage through which the knife passes is of slightly greater width than the knife and of such length as to permit relative movement of the knife, one shoulder of this slot serving to keep the knife 20 blade spaced slightly from the side wall of the can while this carriage side rides upon and against the upper and outer edge of the can top. An angular dog 28 has one end disposed inside the carriage between one side thereof and the spring 23, the opposite end extending through a slot in the carriage side in contact with the frame of the knife, this end of the dog being beveled terminally to form the ear 29 disposed between the prongs 27 of the knife frame and in effect forming a rear end pivot for the knife which is thereby afforded freedom of lateral movement so essential during the cutting operation.

When the spur 2 has pierced the can top and the shank and guard have been disposed in the position shown in Fig. 2, previously described, the blade 26 will have been forced through the can top, the carriage 21 being so positioned upon the shank 1 that the longer bent side of the carriage 40 is disposed against the can periphery. With the left hand the operator now presses the guard downwardly into engagement with the can top to steady same while with his right hand he moves the handle 3 about the can causing the 45 blade to cut the top free from the can. Should the spur 2 not have been placed exactly in the center of the can top the blade will not ride into and bind against the wall of the can, as certain types of can opener blades have been known to do at some point in the cutting operation, as the spring 23 will be partially compressed by the knife and dog thus permitting a movement of the blade inwardly to clear the can wall, this movement being denoted in Fig. 9, the blade being 50 shown in normal position in full lines and in altered position in dotted lines.

In Fig. 12 the knife 31 is of one-piece construction, the ends of the frame being downturned, one end being disposed inside the carriage between 60 one end of the spring 23 and the adjacent side of the carriage while the opposite end is disposed outside the carriage and carries a tooth-shaped blade 30.

Should the blade 30 encounter the side wall of the can the downturned remote end of the knife will compress the spring permitting a movement of the knife blade and knife similar to that shown in Fig. 9. In Figs. 14 and 15 the frame of the knife is "waved" and as the knife is formed of a 70 resilient metal it binds against the shank 1 to yieldingly anchor the knife in any adjusted position upon the shank. A block 24 of rubber is here provided in the carriage and between one end of the rubber block and the carriage side wall one 75

end of the one-piece knife is disposed to provide a compensating knife movement as previously described.

In Figs. 16 and 17 a one-piece knife 32 extends through the sides of the carriage 21, one knife end extending downwardly and being provided with the blade 33 while the opposite end of the knife also downturned and outside the carriage is bifurcated to receive between its prongs the tongue 34 fast upon one end of the flat spring 35 the body portion of which is loop-shaped and disposed within the carriage, one end extending through a side thereof for engagement with the knife. Should this blade 33 encounter an obstacle the spring 35 will permit a movement corresponding to that described relative to the blade 26 in Fig. 9. In opening a can from the position of the opener shown in Fig. 2 the guard is adjusted manually as the handle 3 is moved about the can during the cutting operation. The guard will protect the hand of the operator from contact with the cut edge of the can or of the top thereof and as it is manually retained in engagement with the sides and top of the can during the cutting operation it enables the operator to prevent the can from slipping or overturning and when the can top is completely severed from the can the guard will prevent it from dropping from the spur of the opener into the can. The corrugations upon the under side of the guard are to cause friction between the guard and the can top to permit a better grip upon the can to be obtained. The guard will also protect the hand of the operator while opening cans of hot foods. When the guard is removed from the shank of the opener it may be used as a jar opener. It may be manually pressed about the top of a jar without hindrance from the metal straps and provide an efficient gripping means for the top.

When the spur 2 is to be introduced into the can top center, as shown in Fig. 3 the guard is first reversed so that its lip 10 is disposed away from the handle to avoid interference with the spur at the time this incision is made.

What is claimed is:

1. In a can opener, a shank, a spur at one end thereof, an inverted U-shaped carriage slidable upon said shank, the sides of said carriage being slotted, a knife carried by said carriage and extending through said side slots, and means carried by said carriage between the sides thereof for yieldingly retaining said knife in a predetermined position relative to said carriage, said

means including a dog having pivotal engagement with one end of said knife.

2. In a can opener, a shank, a spur at one end thereof, an inverted U-shaped carriage slidable upon said shank, the sides of said carriage being slotted, a knife extending through the carriage slots, one end of said knife being bifurcated, a blade at the opposite end of said knife, a housing in said carriage, a spring in said housing, a dog engaged by said spring and engaging the bifurcated end of said knife, and a guard carried by said shank.

3. In a can opener, a shank, a spur at one end thereof, an inverted substantially U-shaped carriage slidable upon said shank, the sides of said carriage being slotted, one of said sides being longer than the other and parallel thereto at its free end, one end wall of the slot in said longer side being disposed outwardly from the free end of said side, a knife extending through the slotted portions of said carriage sides for engagement with the said slot end wall, and means carried by said carriage engaging said knife for retaining same in yielding engagement with the said slot end wall.

4. In a can and jar opener, a shank, a knife carried thereby, a spur carried by said shank, an elongated angular slotted bracket strap, a corrugated resilient guard, and a straight bracket strap formed with prongs passing through said guard and through slots in said angular bracket strap, the slots in said angular strap releasably and adjustably receiving said spur.

5. In a can opener, a shank, a knife carried thereby, a headed spur carried by said shank, an elongated angular slotted bracket strap, one of the slots therein having an enlarged portion, a corrugated resilient guard, and a straight bracket strap formed with prongs passing through said guard and through slots in said angular bracket strap, the enlarged portion of the one slot in said angular bracket strap releasably receiving the head of said spur.

6. In a can opener, a shank, a spur at one end thereof, a carriage freely slidable upon said shank, a knife carried by said carriage and extending through one side thereof and terminating outside said carriage in downturned prongs, a housing in said carriage, a coil spring in said housing, and a dog carried by said carriage with one end abutting said coil spring and the opposite end extending through said carriage and terminating in an ear engaging the pronged end of said knife.

GEORGE HENNING GUSTAFSON.
